UNITED STATES PATENT OFFICE.

LUTHER L. KNOX, OF PITTSBURG, PENNSYLVANIA.

FURNACE-DOOR FRAME.

No. 910,924.

Specification of Letters Patent.

Patented Jan. 26, 1909.

Application filed August 6, 1907. Serial No. 387,311.

To all whom it may concern:

Be it known that I, LUTHER L. KNOX, of Pittsburgh, Allegheny county, Pennsylvania, have invented a new and useful Furnace-
5 Door Frame, of which the following is a full, clear, and exact description, reference being had to the accompanying drawings, forming part of this specification, in which—

Figure 1 is a vertical section showing my
10 improved door frame applied to an open-hearth furnace; Fig. 2 is a front elevation of the door frame, partly broken away; Fig. 3 is a view similar to Fig. 2, but showing a modified construction; and Fig. 4 is a vertical cross-section through the upper portion of the
15 detachable rim.

My invention has relation to furnace door frames, and is designed to provide a rim which is so constructed that the portions
20 thereof which are subjected to destructive heat may be readily removed and renewed when burned out, the parts necessary to be renewed in such cases, constituting but a relatively small part of the frame as a whole,
25 so that the renewal may be affected at a comparatively slight cost, and without dismantling the furnace.

A further object is to provide means for obtaining an improved water circulation
30 through the adjustable and renewable portions of the frame, and also to provide means for protecting the brick-work door arch of the furnace.

The precise nature of my invention will be
35 best understood by reference to the accompanying drawings which will now be described, it being premised, however, that various changes may be made therein by those skilled in the art without departing
40 from the spirit and scope of my invention.

In the drawings, the numeral 2 designates the brick-work of an open-hearth furnace, 3 the door opening of the furnace, and 4 a part of the hearth or bottom thereof.

45 5 designates a main door frame member which is secured to the structural building of the furnace, and which is formed with the cheeks or flanges 6 which form guiding surfaces for a vertically-sliding door and with
50 an inwardly extending flange or shelf 5^a which assists in supporting the top wall of the door arch. This door may be of any suitable character, but I have shown it as of the form described and claimed in my

Patent No. 864,763, dated August 27th, 55
1907, in which it is composed of a hollow body portion 7, a refractory backing 8, and a hollow surrounding rim portion 9 which is detachably secured to the body, suitable connections 10 being provided for circulating a cooling fluid through the body and rim.

The main frame member 5 is formed with a door opening 11 which is somewhat larger than the opening 3 of the furnace in order to 65 receive therein, a supplemental frame member 12. This supplemental frame member is a rim-like structure having an arched top portion and depending legs, and is constructed to fit within the marginal portion of the opening 11 against the brick-work 2 of the furnace front, with its outer surface substantially flush with the surfaces 13 of the main frame member 5 upon which the door slides. The supplemental frame member 70 is detachably secured within the opening 11 in any suitable manner. In the drawings, I have shown it as provided with the laterally-extending lugs 14 which enter recesses 15 in the main frame member 5, and which are secured by keys or pins 16. The upper portion of the supplemental frame member 75 has an inward extension 17 which forms a lining for the brick-work arch of the furnace over the opening 11 throughout its entire 80 thickness.

An important object of my invention is to provide for the circulation of water or other cooling medium throughout the entire extent of the supplemental frame member; and 90 for this purpose the latter is cast hollow with an intermediate partition wall 18 which is continuous except at the lower portions of the legs where circulating openings 19 are provided.

95 20 designates a supply pipe for the water or other cooling fluid which is detachably connected to the central portion of the supplemental frame member, and which opens into the inner of the two compartments 100 formed by the wall 18. 21 is an outlet pipe which communicates with the outer of the two compartments. These pipes are conveniently carried upward in front of the furnace within a recess 22 formed in the main frame member 5, so that the door will slide 105 freely over them.

The circulation of water is clearly indi-

cated by the arrows in Fig. 2. The water delivered by the pipe 20 flows in both directions in the inner compartment, thence out into the two legs of the supplemental frame, 5 around the lower ends of the partition wall, and thence upwardly from both sides to the outlet pipe 21. The partition wall 18 is also extended into the extension 17 which it divides into inner and outer compartments. 10 The upper wall of each of these compartments is preferably slightly inclined upwardly toward the front of the furnace, as indicated in Fig. 1, so that the water therein as it becomes heated will tend to rise and be 15 replaced by cooler water.

By the construction described, I am enabled to provide for a continuous circulation throughout all portions of the supplemental frame without the necessity for connecting 20 the legs thereof at the bottom. Such a connection is objectionable inasmuch as it necessarily forms a part of the floor of the door opening, and is subject to rapid wear and breakage in charging and discharging the 25 furnace. By arranging the circulating passages in the frame member, as shown and described, I am enabled to do away with the use of this connection, and can extend the floor plate or sill 23 of the furnace in the 30 manner shown in Fig. 1, so as to receive the wear in charging and discharging the furnace. The construction also insures a complete circulation through the upper central portion of the supplemental frame member 35 at the point where the heat is greatest.

In the modification shown in Fig. 3, the upper compartment of the supplemental frame member 12 is divided at the top by a transverse vertical partition 24. The sup- 40 ply pipe 20^a communicates with this outer compartment at one side of the partition 24, while the outlet pipe 21^a communicates with said compartment upon the opposite side of the partition 24. In this form, the water 45 circulation, as shown by the arrows is from the pipe 20^a downwardly into one leg of the frame in the outer compartment thereof, thence around the lower end of the partition wall 18^a, thence upwardly and around 50 through the entire length of the inner compartment, thence around the outer end of the partition 18^a, and upwardly in the outer compartment to the outlet pipe 21^a. The partition 18^a is preferably provided with a 55 plurality of small perforations 25 adjacent to the partition 24, for the purpose of permitting the escape of steam bubbles from the inner compartment. This construction provides for a circulation which has all the 60 advantages of the construction shown in Figs. 1 and 2, except that the cooling water becomes heated sometime before reaching that portion of the frame which is exposed to the greatest heat.

65 A further advantage which results from

the use of the separable supplemental frame member is that all portions thereof are subjected to approximately the same heat. This to a large extent overcomes the cracking and breaking which frequently occurs in the 70 ordinary door frames, due to the fact that the portions immediately surrounding the door openings are subjected to much greater heat than those portions which are more distant from the door opening. This unequal 75 heating causes unequal expansion.

What I claim is:—

1. A furnace door frame, consisting of a main frame member fixedly secured to the furnace and having an opening therethrough 80 larger than the opening of the door, and a detachable supplemental frame, consisting of a rim-like structure fitting within the said opening and forming the top and sides but not the bottom thereof, and having a continuous water-circulating passage therein, said main and supplemental frame members having door-seating surfaces in substantial vertical alinement, substantially as described. 85

2. A furnace door frame consisting of a 90 main metallic frame member secured to the brick wall of the furnace and having a door opening therein, and a supplemental frame member of rim form removably fitted within the said opening, and forming the top and 95 sides, but not the bottom thereof, said supplemental frame member having inner and outer circulating compartments, the inner compartment being continuous throughout the member; substantially as described. 100

3. As a new article of manufacture, a rim structure for furnace door frames consisting of an arch with depending legs disconnected at their lower ends, and having therein inner and outer compartments, the inner compartment being continuous through the arch and above the legs; substantially as described.

4. In a furnace door frame, a main frame member having a door or opening therein, and a supplemental frame member consisting of a rim structure arranged to fit within said opening, and having inner and outer water circulating compartments, the inner compartment at least being continuous around the entire rim structure, together with circulating connections for said compartments; substantially as described.

5. In a furnace door frame, a main frame member, and a supplemental frame member consisting of a rim-like structure arranged to fit removably within the door opening of the main frame, and having an inward extension at its upper portion which extends into the furnace wall and forms a lining for the arch of the door opening thereof, together with means for circulating a cooling fluid through said supplemental frame; substantially as described.

6. In a furnace door frame, a main frame member, and a supplemental frame member

consisting of a rim-like structure arranged to fit removably within the door opening of the main frame, and having an inward extension at its upper portion which projects into the 5 wall of the furnace and forms a lining for the arch of the door opening thereof, together with means for circulating a cooling fluid through said supplemental frame; and also

through the inward extension thereof; substantially as described.

In testimony whereof I have hereunto set my hand.

LUTHER L. KNOX.
